CLAIM

The ornamental design for a compartmented packaging container for dental materials or the like, as shown.

DESCRIPTION

FIG. 1 is a top perspective view of a compartmented packaging container for dental materials or the like showing our new design;

FIG. 2 is a side elevational view, similar to all other elevational views;

FIG. 3 is a top plan view;

FIG. 4 is a bottom plan view; and

FIG. 5 is a view similar to FIG. 1 but showing the cover removed.

FIG-1

FIG-2

FIG-3

FIG-4

FIG-5
